(57) **CLAIM**

The ornamental design for a connector for nerve stimulator, as shown and described.

DESCRIPTION

FIG. 1 is a top front perspective view of a connector for nerve stimulator, showing our new design;

FIG. 2 is a bottom rear perspective view of the connector for nerve stimulator of FIG. 1;

FIG. 3 is a front elevation view of the connector for nerve stimulator of FIG. 1;

FIG. 4 is a rear elevation view of the connector for nerve stimulator of FIG. 1;

FIG. 5 is a right elevation view of the connector for nerve stimulator of FIG. 1;

FIG. 6 is a left elevation view of the connector for nerve stimulator of FIG. 1;

FIG. 7 is a top plan view of the connector for nerve stimulator of FIG. 1; and,

FIG. 8 is a bottom plan view of the connector for nerve stimulator of FIG. 1.

The connector for nerve stimulator features shown in broken lines are unclaimed environment, and form no part of the claimed design.
